UNITED STATES PATENT OFFICE.

GEORGE A. COWGILL, OF EUPHEMIA, OHIO.

CARPET-CLEANER.

SPECIFICATION forming part of Letters Patent No. 744,721, dated November 24, 1903.

Application filed March 14, 1903. Serial No. 147,809. (No model.)

To all whom it may concern:

Be it known that I, GEORGE A. COWGILL, a citizen of the United States, residing at Euphemia, in the county of Preble and State of Ohio, have invented a new and useful Carpet-Cleaner, of which the following is a specification.

My invention relates to carpet-cleaners, and is an improvement on my carpet-cleaner patented June 18, 1901, No. 676,460, and the cleaning devices for which patent was applied for July 13, 1901, Serial No. 68,209, and April 24, 1902, Serial No. 104,483.

The object of the present improvement is to provide improved means for actuating the beaters, for conducting the air-blast to and beneath the carpet, and for preventing injury to the carpet by the beaters.

The invention consists in a fan-casing of peculiar construction, the carpet being cleaned forming a portion of the front wall of the fan-casing, beaters arranged in an enlargement of the casing, the air-blast passing downward between the beaters and thence under and beyond the carpet being cleaned; also, in the means for actuating said beaters and means for limiting the motion of the beaters, as hereinafter described and claimed.

In the accompanying drawings, Figure 1 is a side elevation of that portion of my device containing the improvements herein described. Fig. 2 is a plan view, a portion of the fan-casing being broken away and in section. Fig. 3 is a detail sectional view showing the interior of the chamber containing the beaters and means for preventing dust from escaping therefrom. Fig. 4 is a perspective detail view of a part of the beater-shaft, one of the beaters, and attachments connected to the shaft. Fig. 5 is a detail perspective view showing the means employed to actuate the beater-shaft. Fig. 6 is a detail section, the spring-pressed roller and bracket being in elevation. Fig. 7 is a detail perspective view showing the stop-pin carried by the beater-shaft. Fig. 8 is an enlarged detail view illustrating the construction of the rocker-bar and showing the springs connected at one end to the bar and at the opposite ends to the casing.

In carrying out my improvements I employ base-beams A, on which are mounted the ver-

tical carpet-carrying frame A' and the frame A², carrying the fan-casing.

Suitable rollers carried by the frame A' carry the carpet A³ to be cleaned, all of which is fully described in the applications heretofore mentioned.

The fan-casing comprises a cylindrical chamber B, arranged in the rear of the carpet to be cleaned. At its forward side this chamber communicates with an air-passage B', having forwardly-diverging side walls, the part B' being at its forward end nearly the width of the carpet, the carpet forming the front wall of the casing. Immediately below and having free communication with the passage B' is the beating-chamber B², closed by permanent walls at the rear and sides and closed in front by the carpet being acted on by the beaters. From the lower part of this chamber extends a casing B³, forming an air and dust passage beneath the carpet, and this passage opens into the dust-chamber described in my former applications for patent and not forming a part of the present improvements. All these chambers and passages B, B', B², and B³ are practically continuations of one common casing. A fan of any desired construction is placed in the chamber B, mounted on a shaft C and driven by belting C', running to the pulley C². Means are of course provided to supply air to said chamber. Through the chamber B² pass two parallel shafts D' and D², journaled in the frame A², as is the shaft C.

A belt E, running over pulleys E' E², drives a shaft E³, which carries a pulley E⁴. The shaft D' carries pulleys D³, D⁴, and D⁵, and the shaft D² carries a pulley D⁷. A belt E⁵ runs from the pulley E⁴ to the pulley D³.

Suitable belts run from the pulleys D⁴ to D⁷ and D⁵ to the pulley F', carried by the shaft F, on which is carried the roller actuating the carpet. A plurality of curved beaters G are arranged on the shaft D². A compound-curved rocker-bar H is rigidly secured to the shaft D², adjacent one end, and at each end of the rocker-bar is secured one end of a coil-spring H', the other end of the spring being secured to the side of the casing. The tendency of these springs is to throw the beaters against the carpet. A stop-pin H² is secured on the shaft D² adjacent the rocker-

bar, and when the shaft D^2 is rocked the pin contacts with a stop H^3 , having an inclined rubber face H^4 , which stop prevents the beaters from tearing through or injuring the carpet.

5 Between the rocker-bar and the beaters the upper part of the shaft D^2 is cut out, forming a flat surface J , to which is pivoted a laterally-projecting bar J' , normally held at right angles to the shaft D^2 by a coiled spring J^2 , secured at one end to the bar and at the opposite end to the shaft D^2 .

The shaft D' is transversely recessed, and a knocker-bar K is rigidly secured in the recess extending on each side of the shaft and at 15 right angles thereto. This bar is reduced in width intermediate its ends, whereby the end portions K' project laterally beyond the intermediate outer side portion of the bar. This bar is so arranged that as the shaft D' revolves 20 the projecting ends of the bar K will strike the upper surface of the bar J , forcing it downward, rocking the shaft D^2 , and drawing the beaters away from the carpet; but as soon as the end K' passes out of reach of the bar 25 J the springs H' immediately throw the shaft D^2 in the opposite direction and bring the beaters against the carpet, the pin striking the stop H^4 . The construction of the parts are such that it is obvious that the shaft D^2 30 will be rocked twice for each revolution of the shaft D' .

A lever L , carrying a pawl engaging a rack-bar L' , is located at one side of the frame A^2 , and a cable L^2 , carried over suitable pulleys, 35 extends from this lever to the bar J . By throwing the lever rearward the bar is drawn to one side out of the path of the knocker-bar.

The shaft D^6 is journaled in a bracket A^4 on the frame A' and extends transversely 40 just above the forward edge of the top of the passage B' . This shaft carries a brush D^8 , which bears against the carpet and prevents the latter from rubbing against the edge of the casing and also prevents air from the fan 45 escaping between the edge and the carpet. To prevent air and dust escaping into the space between the top of the passage B^3 , a roller M is arranged of a size sufficient to fill this space and is journaled in spring-pressed 50 bearings M' , by which means it is held against the carpet, so that no dust passes between the roller and the carpet, and it also serves to keep the carpet in contact with the actuating-roller F' . The belt C' is driven from any 55 suitable source of power, and it will be noted that by means of the lever L motion of the rock-shaft D^2 can be stopped without inter-

ference with any of the belts or stopping any of the remaining shafts. It will also be noted that the draft from the fan strikes the carpet 60 just above the beaters and travels downward along the surface being beaten, thus carrying the dust away as rapidly as it is loosened from the carpet.

Having thus fully described my invention, 65 what I claim as new, and desire to secure by Letters Patent, is—

1. A device of the kind described comprising fan and beating chambers, a passage extending from the fan to the beating-chamber 70 and opening downward into the latter, a rock-shaft carrying beaters arranged in the beating-chamber, a dust-passage leading from the said chamber, means for passing a carpet in the path of said beaters, means for preventing 75 air and dust from escaping between the carpet and the edges of the beating-chamber, a fan in the fan-chamber, and means for driving same.

2. A carpet-cleaning machine comprising 80 a beating-chamber, a dust-conduit, leading forwardly from the lower portion of the beating-chamber, a spring-pressed roller above said conduit adapted to bear on the carpet and prevent dust escaping into the space between the carpet and conduit, means for beating 85 said carpet, and means for passing an air-blast through said beating-chamber.

3. In a device of the kind described, a beating-chamber, beaters arranged therein, means 90 for passing a carpet vertically before said beaters, means for directing an air-blast against the carpet above the beaters, an air and dust discharge conduit leading from the beating-chamber below the beaters, said air-blast passing downward along the surface of the carpet between the beaters, and means 95 for actuating the beaters.

4. The combination with a beating-chamber adapted to receive a carpet, a rock-shaft 100 arranged therein, curved beaters on said shaft, spring-actuated means for throwing said beaters toward the carpet, a bar normally held at right angles to said shaft, a parallel revoluble shaft, a knocker thereon 105 adapted to engage the bar on the rock-shaft and draw the beaters away from the carpet, means for drawing the bar from the path of the knocker, and means for limiting forward movement of the beaters.

GEORGE A. COWGILL.
